UNITED STATES PATENT OFFICE.

WILLIAM E. KELLY, OF CLEVELAND, OHIO.

REAMER.

1,246,607.

Specification of Letters Patent. Patented Nov. 13, 1917.

Application filed October 23, 1916. Serial No. 127,067.

To all whom it may concern:

Be it known that I, WILLIAM E. KELLY, a citizen of the United States, residing at Cleveland, county of Cuyahoga, and State of Ohio, have invented a new and useful Improvement in Reamers, of which the following is a specification.

My invention relates to reamers of the flat type and method of holding the same in a bar or holder.

The object of my invention is an efficient and economical apparatus for machining holes.

I attain this object by the mechanism illustrated in the accompanying drawings in which Figure I is a general side view of an adjustable reamer which embodies my invention, Fig. II is an end view of Fig. I, Fig. III is a plan view of Fig. I, Fig. IV is a section on line 4-4 of Fig. I, Fig. V is a section on line 5-5 of Fig. II, and Fig. VI is a section on line 6-6 of Fig. III.

Similar reference characters refer to similar parts throughout the several views.

25 The reamers and boring tools heretofore made, particularly the floating type, had no provision to prevent the cutters from getting out of alinement with the axis of the tool and the work. Such tools, therefore, very often do get out of alinement and ream or bore a hole larger than the size of the tool; sometimes, very often in fact, such a tool will, very often, even cut a groove in the reamed or bored hole while it is backed out 35 of the hole. These disadvantages tend to increase the inefficiency of the tool and the amount of spoiled work.

The present invention aims to overcome these difficulties in an efficient, economical, and practical manner.

Referring now particularly to the drawings: The reamer shown here has the shank or holder 1 which has a slot which is adapted to receive the cutter-block 2 slidably sidewise but is somewhat longer than the cutter-block 2 lengthwise to permit the block 2 to rock in the slot. Traversely to this slot, the holder 1 has two openings to receive the screws 3 as clearly seen in Fig. VI. Near the front end, the holder 1 has an opening to receive the pilot-cutter 12 and in proper relation thereto the front end of the holder 1 has an opening which is adapted to receive the clamp-bushing 13 and the clamp-screw 14 as is clearly seen in Fig. V. The other portions of the holder 1 may be

made to suit any particular purpose, machine, or appliance.

The cutter-block 2 fits slidably into the said slot in the holder 1 and has two openings which are adapted to the taper portions of the screws 3 as is clearly seen in Fig. VI. It may be noted here that these openings and screws 3 are spaced rather far apart longitudinally which construction enables the cutter-block to float or rock freely and prevent oversize holes as will appear hereinafter. In the front face, the cutter-block 2 has the notch 7 which is larger than the size of the pilot-cutter 12 so that the cutter-block 2 can float or rock in the slot without interference of the pilot-cutter 12. On opposite sides of the cutter-block 2 the cutter-blades 8 are mounted. It is preferred that both longitudinal edges of these blades 8 be beveled and that the slots in the cutter-block 2 into which these blades 8 fit be beveled to suit. At a convenient point along one of these beveled edges and a suitable distance away therefrom, the cutter-block 2 has two openings to receive the clamping means which holds the blades 8 in place as is clearly seen in Fig. IV. Each clamping means consists of the bushing 9 which fits into a corresponding opening in the cutter-block 2 and the screws 10 which also fits into a corresponding opening in the cutter-block 2 and which is threaded into the bushing 9. The cutter-block 2 further has two openings in longitudinal alinement with the inclined cutter-blades 8 into which the adjusting-screws 11 fit snugly.

The operation of this particular reamer is as follows:

In order to lock the pilot-cutter 12 in position, tighten the clamp-screw 14 at which time the taper bushing 13 is moved inwardly and wedges the pilot-cutter 12 against its seat in the holder 1. In order to release the pilot-cutter 12, for the purpose of sharpening, adjusting, or other reasons, release the clamp-screw 14 at which time the clamp-bushing 13 will also be released and the cutter 12 may be shifted or removed readily. This method of holding the pilot-cutter is preferred over the usual set-screw or wedge although either may be employed for the purpose. The disadvantage with set-screws is that the cutter may be shifted while the screw is being tightened owing to the rotation of the screw, the disadvantage with a wedge is that the cutter may be shifted when

the wedge is driven in. These disadvantages I overcome by the clamp-bushing 13 which has no tendency to shift the pilot-cutter 12 longitudinally.

In order to adjust and lock the cutter-blades 8, release the screws 10, adjust the cutters 8 to their required position by means of the adjusting-screws 11, then tighten the screws 10 at which time the bushing 9 will be drawn into its opening in the cutter-block and the beveled and flat side of the bushing 9 will force the blade 8 against its seat and hold it there firmly.

The cutter-block 2 may be held either 15 floatingly or rigidly in the holder 1. In order to hold the same rigidly, tighten both screws 8 at which time the taper portion of the screws 8 engage the taper openings in the cutter-block 2 snugly and the same will be held firmly and centrally in the holder 1. In order to hold the cutter-block 2 floatingly in the holder 1, release each screw 8 to suit the amount of float desired. When a cutter-block is held rigidly in a holder it has no 20 tendency to cock or get out of alinement, but when it is held floatingly some means must be provided to keep it in alinement. This I accomplish by spacing the screws 8 rather far apart and by tightening them so that the taper portion of the rear screw 3 has just sufficient clearance in its opening to let the cutter-block 2 swivel on the rear screw 3 while the taper portion of the front screw 3 may be given sufficient clearance in its opening to provide any desired amount of float. With this arrangement, the rear part of the cutter-block and consequently the rear part 25 of the cutter-blade can not move outwardly farther than the front part thereof since the cutter-block is substantially hinged near its rear end and the rear end of the cutter-blade can do no damage to the hole which is being reamed or bored.

Heretofore considerable trouble and expense has been incurred to produce proper holes, particularly in quantity production. The present invention provides a means to produce proper holes by hinging the cutter-block at its rear end and mounting the same 50 in such a manner that it may be held or used either floatingly or rigidly which is a decided advantage. This advantage is further increased by the pilot-cutter which trues up the hole before reaming and does so with

very little expenditure of time which is also 55 a decided advantage since it aids the blades materially.

It is understood that the reamer which is shown in the drawings and which was selected to illustrate my invention and for the title of this invention is by no means the only embodiment of my invention and that various changes and modifications may be made within the scope of the appended claims without limiting myself to the precise 60 construction shown and described.

I claim:

1. A cutter-block hinged near its rear end and having means located at its front end to hold the same within desired limits. 70

2. A cutter-block having an opening near its rear end and an opening near its front end, a pin in the opening near the rear end upon which pin the rear end of the cutter-block can swivel, and an apparatus in the 75 opening near the front end whereby the front end of the cutter-block can be held either floatingly or rigidly.

3. In an apparatus of the character described, the combination of a holder, a cutter-block in the holder, the rear portion of the cutter-block hinged in the holder and means located in the front portion of the cutter-block to hold the same within desired 80 limits. 85

4. In an apparatus of the character described, the combination of a holder, a cutter-block in the holder, the rear portion of the cutter-block hinged in the holder, and a pilot-cutter in the holder ahead of the cutter-block. 90

5. In an apparatus of the character described, the combination of a holder, a cutter-block in the holder, the rear portion of the cutter-block hinged in the holder, and means whereby the front portion of the cutter-block is adapted to be held either floatingly or rigidly in the holder. 95

6. In an apparatus of the character described, the combination of a holder, a cutter-block adapted to be held either rigidly or floatingly in the holder, and a pilot-cutter in the holder ahead of the cutter-block. 100

WILLIAM E. KELLY.
